CLAIM

The ornamental design for a sofa, as shown and described.

DESCRIPTION

FIG. 1 is a perspective view of a first component of a sofa showing my new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second component of the sofa shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of a third component of the sofa shown separately for ease of illustration;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a perspective view of a fourth component of the sofa shown separately for ease of illustration;

FIG. 26 is another perspective view thereof;

FIG. 27 is a front elevational view thereof;

FIG. 28 is a rear elevational view thereof;

FIG. 29 is a left side elevational view thereof;

FIG. 30 is a right side elevational view thereof;

FIG. 31 is a top plan view thereof;

(Continued)

FIG. 32 is a bottom plan view thereof;
FIG. 33 is a perspective view of a fifth component of the sofa shown separately for ease of illustration;
FIG. 34 is another perspective view thereof;
FIG. 35 is a front elevational view thereof;
FIG. 36 is a rear elevational view thereof;
FIG. 37 is a left side elevational view thereof;
FIG. 38 is a right side elevational view thereof;
FIG. 39 is a top plan view thereof;
FIG. 40 is a bottom plan view thereof;
FIG. 41 is a perspective view of a sixth component of the sofa shown separately for ease of illustration;
FIG. 42 is another perspective view thereof;
FIG. 43 is a front elevational view thereof;
FIG. 44 is a rear elevational view thereof;
FIG. 45 is a left side elevational view thereof;
FIG. 46 is a right side elevational view thereof;
FIG. 47 is a top plan view thereof;
FIG. 48 is a bottom plan view thereof;
FIG. 49 is a perspective view of the first component, the third component, the fourth component, and the fifth component where the first component, the third component, the fourth component, and the fifth component are assembled together;
FIG. 50 is a perspective view of the first component, the third component, the fourth component, and the sixth component where the first component, the third component, the fourth component, and the sixth component are assembled together;
FIG. 51 is a perspective view of the second component, three third components, the fourth component, and the fifth component where the second component, the three third components, the fourth component, and the fifth component are assembled together;
FIG. 52 is a perspective view of the second component, four third components, the fourth component, and the fifth component where the second component, the four third components, the fourth component, and the fifth component are assembled together; and,

FIG. 53 is a perspective view of the second component, two third components, and the sixth component where the second component, the two third components, and the sixth component are assembled together.
